EXTENSIBLE AND FLEXIBLE BARRICADE

Harry B. Moore and Clarence C. Hunter,
Rocky Mount, N. C.Application June 20, 1938, Serial No. 214,799
Renewed June 6, 1940

5 Claims. (Cl. 256—1)

This invention relates to barricades, particularly adapted to street or road work and it consists in the constructions, arrangements, and combinations herein described and claimed.

- 5 It is the cardinal purpose of the invention to provide a barricade which is collapsible for ready and easy transportation, and when erected will afford full safety to vehicular traffic and pedestrians.
- 10 It is also an object of the invention to provide a barricade in which the supporting frame when in use, also functions as a means for housing the barricade when in collapsed condition.

15 It is a still further object of the invention to provide a barricade in which the extremities of the barricade are flexible, preventing damage to a vehicle which might encounter that portion of the barricade.

20 A further object of the invention is to provide a barricade of a flexible character which may be shaped to circular formation for protection of man-holes and the like.

Additional objects, advantages and features of 25 invention will be apparent from the following description and accompanying drawing, wherein

25 Figure 1 is a plan view of the barricade in collapsed shipping position.

Figure 2 is a perspective view of the barricade in use.

30 Figure 3 is a plan view of the barricade when erected for protection of a man-hole or the like.

Figure 4 is a cross section on the line 4—4 of Fig. 2.

35 Figure 5 is a side elevation of a supporting leg of the barricade.

Figure 6 is a front view thereof.

Figure 7 is a detail of the supporting foot of the leg.

40 Figure 8 is a fragmentary detail illustrating the mounting of a signal jewel.

Figure 9 is an enlarged cross section through a pair of the lazy tong links.

45 Attention is first invited to Figure 1 of the drawing, wherein the barricade 10 is shown in collapsed position and confined within a frame structure 11, which, in the present instance, comprises five hingedly connected sections 12, 13, 14, 15 and 16, which in their collapsed position form a housing for the barricade, as will appear as the 50 description proceeds.

The sections 12—16 are U-shaped channel bars of light construction, hinged together as indicated at 17, 18, 19 and 20. The top channel bar 14 and the lower bars 12 and 16 are of substantially equal lengths, but the bars 12 and 16 are

individual bars and jointly aggregate the length of the bar 14, their abutting end edges meeting medially of the length of the bar 14. Thus, it will be seen that the bars 12 and 16 lie parallel to the bar 14 constituting the longitudinal sides of the frame and that the sections 13 and 15 which are of lesser length constitute the end portions of the housing.

The barricade 10 in the present instance is shown as of an extensible structure, of the well known lazy tong principle comprising pivotally connected links 21, and since this structure is well understood, a detailed description is not thought necessary for a full understanding of the invention. However, it should be understood that the links 21 are extensible in a lengthwise direction to effect a barricade, and since the links are constructed of a flexible steel, sufficient flexibility is inherent to permit the flexing of the links into a circular formation for encircling a 20 man-hole or the like, as shown in Figure 3.

The channel bar 14 has an aperture formed intermediate its length adapted to align with an aperture of the upper pivotally connected ends of a pair of lazy tong links, and between the registered apertures a cotter pin 22 is inserted, insuring retention of the barricade 10 within the channel bar. The end channel bars 12 and 16 are similarly provided with apertures adjacent their ends, adapted to register with and to receive cotter pins 22'.

As clearly shown in Figure 9, the various pivotal connections of the links 21 at their extremities as well as their medial connections comprise a spacer washer 23 for separation of the links 21, 35 each link 21 being apertured to receive an eyelet 24, respective ends thereof being upset to secure the links.

With further consideration to Figure 1, in order to erect the barricade to the position shown 40 in Figure 2, the cotter pins 22' are removed from their respective eyelets, as is the cotter pin 22, which will allow the sections 12, 13, 14, 15 and 16 to be swung upon their pivots 17, 18, 19 and 20, into longitudinal alignment, as shown in Figure 45

2. The barricade 10 is next moved to its extended position, which may be accomplished by grasping the knobs 25 and exerting an outward simultaneous movement to the links, until a desired extension of the barricade has been attained. The aligned sections 12, 13, 14, 15 and 16 are now presented over the upper end portions of the links 21, so as to register eyelets of the links with apertures of the sections 12, 14, and 16, when a cotter pin is again inserted through 55

aligned apertures and eyelets. Thus, the barricade will be maintained in extended position.

In order to support the barricade, four detachable legs 26 are provided, constructed for a slip-on connection with lower extremities of certain links 21 of the barricade. The legs 26 comprise an upwardly opening socket 27 of a width to slidably receive a link 21 therein, and in the present instance, the socket is shown as formed from a blank of metal having flanges 28 between which the lower end of a link is received. The extended position of the barricade obviously presents the links 21 at an angle and therefore the socket 27 will be fixed to the legs 26 at such angle as to readily accommodate the links to be engaged and preferably the mutually hinged links will be engaged by respective legs and sockets in order to provide a stable structure.

The base portions of the legs 26 may have any desired formation for support of the barricade, and in Figure 2 the leg 26 terminates in a pointed portion 29 adapted to penetrate a road surface, while in Figures 5 and 6, the leg terminates in diverging members 30 and 31. The member 30 is constructed for penetration of a surface, while the member 31 is adapted to rest upon a surface and is provided with an aperture 32 for reception of an anchorage bolt or fastening 33.

From the foregoing, it will be readily seen that the legs may be readily detached or attached to links of the barricade, and preferably, the legs are arranged in opposed pairs, as clearly shown in Figure 2, and in practice, it has been found desirable to place the legs well inwardly of the extremities of the barricade, for the reason that by such placement of the legs flexible end portions of the barricade are provided, as indicated at 34 and 35, permitting forcible contact with the ends by a vehicle, without damage to either the barricade or the vehicle, since the ends of the barricade will readily flex, permitting passage of the vehicle until brought to a stop.

It is often necessary to place a barricade or guard around a man-hole or the like, and the present structure is susceptible to such use, as illustrated in Figure 3, and in such use, the channel members 12-16 are not used. The barricade in this instance is flexed to a circular shape, the extremities of the links 21 being overlapped to register apertures of the links for engagement of cotter pins 25a. The supporting legs 26 will be engaged with links of the barricade, as previously described, but they will be equally and circumferentially spaced around the periphery of the barricade.

Reflecting prisms have become generally used as traffic signal devices and it will be apparent that such prisms may be readily incorporated with the present barricade. Such prisms may be incorporated upon the barricade in various manners, but in Figure 8 we have illustrated a bolt 34 of a size to be received through any of the eyelets 24, bearing a reflecting prism 35. These prisms may be arranged upon the barricade in any desired manner, for instance, the prisms may be arranged in staggered relation, red and green

alternating, or one end of the barricade may comprise all green signals and the other end red signals.

The legs 26 when detached may be secured to the barricade, when in collapsed position, by means of brackets 36 secured by bolts in suitable eyelets of the barricade.

When it is desired to collapse the barricade, the cotter pins 22-22' are removed, permitting removal of the channel sections 12-16, when the barricade may be collapsed by grasping the knobs 25 and moving them toward each other. When the barricade has been fully collapsed, the barricade is placed within the channel sections 12-16. The sections are then moved so as to encompass the barricade when the cotter pins 22-22' are replaced to effectively house the barricade. In order to facilitate handling, the section 14 may include a handle member 37.

While we have shown and described a preferred construction, this is by way of illustration only, and we consider as our own all such modifications as fairly fall within the scope of the appended claims.

We claim:

1. A barricade for highways and the like comprising a series of link members for simultaneous extension and retraction, a hinged U-shaped frame member engageable with and secured to the upper ends of certain link members and detachable support means engageable with link members inwardly of the extremity of the extended position of the link members whereby to provide freely flexible end portions.

2. A barricade comprising a hingedly connected U-shaped frame member, certain of said sections having transversely extended apertures, a series of pivotally connected link members arranged for simultaneous extension and retraction, said link members having apertures for registry with apertures of the sections, a pin member engageable through registered apertures of the frame member and links, and detachable support means engageable with certain of the link members.

3. The structure of claim 2 in which the support means include a socket at one end for reception of a link member, the opposite end having surface penetration and ground anchorage means.

4. The structure of claim 2 in which the link members include light reflecting prisms.

5. A barricade for highways and the like comprising a series of link members, for simultaneous extension and retraction, a hinged U-shaped frame member engageable with the upper ends of the link members, means for securing the frame to certain of said link members, detachable support means engageable with certain link members, said support means having a socket for reception of the link, and said support means being positioned upon opposite sides of links of the barricade and including a penetration point and an anchorage foot.
